UNITED STATES PATENT OFFICE.

WILLIAM E. HOYT, OF NEW YORK, N. Y.

SAD-IRON.

1,109,528.

Specification of Letters Patent.

Patented Sept. 1, 1914.

Continuation in part of application Serial No. 703,046, filed June 11, 1912. This application filed January 22, 1914. Serial No. 813,721.

To all whom it may concern:

Be it known that I, WILLIAM E. HOYT, a citizen of the United States, residing at New York, New York county, and State of New York, have invented and discovered 5 certain new and useful Improvements in Sad-Irons, of which the following is a specification.

In the use of sad irons conditions are 10 sometimes favorable to the use of gas as a heating agent, while under other conditions charcoal, or similar fuel, is more convenient for such purposes.

The object of my said invention is, therefore, to provide a sad iron which is capable 15 of use either with gas or charcoal as a fuel, and it consists, further, in certain details of construction relating particularly to the gas burner whereby these objects are advantageously attained, all as will be hereinafter 20 more fully described and claimed.

Referring to the accompanying drawings which are made a part hereof, and on which similar reference characters indicate similar 25 parts, Figure 1 is a side elevation of a sad iron of my improved construction with the gas burner attachment thereon, Fig. 2 a central longitudinal section through the same, Fig. 3 a rear elevation thereof, and showing 30 the outline of the removable door in dotted lines, Fig. 4 a horizontal section looking downwardly from the dotted line 4-4 in Fig. 2, with fender plate 40 omitted, Fig. 5 a horizontal section through the gas burner 35 attachment, Fig. 6 a detail view of a form of rear door for the combustion chamber to be used when charcoal is employed as the fuel, Fig. 7 a detail view of the front end of the gas burner, Figs. 8 and 9 are cross sections on the dotted lines 8-8 and 9-9, respectively, in Fig. 5.

In said drawings the portions marked A represent the body of the sad iron, B the handle, C a heat deflecting plate, D my improved gas burner attachment, and E the substitute rear door for use when charcoal is employed.

The body A is a casting of suitable form and arrangement, being hollow to form a 50 combustion chamber and provided with a grate a_1 and a flue a^1 with a damper 10 therein. Suitable air openings 11 controlled by a sliding valve 12, are provided on each side of the combustion chamber, as indicated. 55 A strip of sheet metal 25 bent in the form of

the interior of the chamber within the iron extends around the interior of said chamber and is spaced from the sides thereof to form air passages from the openings 11 on either side to a point adjacent to the sides of the 60 grate on the bottom of said chamber.

The handle B and deflecting plate C are of any appropriate or approved form and need no special description herein.

A fender plate 40 extends horizontally 65 through the combustion chamber above the burner and near the upper portion of the chamber, being supported on appropriate legs 41 and 42 and serving to establish an air chamber above the plate and protect the 70 upper portion of the iron from the heat while at the same time deflecting the heat downwardly.

The gas burner attachment D comprises a 75 plate adapted to be inserted in vertical grooves on each side of the rear opening leading into the combustion chamber in the body A and serves as a door for said opening. As will be noted by an inspection of Fig. 3, the sides of the rear opening leading 80 into the combustion chamber are tapered somewhat from the top inwardly toward the bottom, but said opening is formed somewhat wider at the top than at the bottom. The edges of door D, as indicated by 85 dotted lines, are correspondingly tapered, and at their upper ends have laterally projecting wings 26, so that when in its lowermost position the edges of said door will be retained by the flange around the sides and bottom of said opening, but when raised slightly, sufficiently to disengage the laterally projecting wings 26 at the upper end of the side edges of said door, the door will 90 be released from said flanges and permitted to pass freely through the opening. Said door is formed with an opening d through 95 its upper portion above the burner to admit air, but is otherwise adapted to close said opening when in position. The gas burner proper, D^1 , is formed integral with the door, or cast in piece therewith, and extends on each side thereof, its outer end being internally screw-threaded for attachment to a pipe section 13, and its inner end being 100 fan-shaped and divided into two discharge openings 14, extending at an angle from the central opening and divided by an angle piece 15 between them, as best shown in Fig. 5. Said gas burner extends at an angle from 110

the door downwardly toward the bottom of the iron, as best shown in Fig. 2. The pipe section 13 is provided with air inlet openings 16 near its outer end and a regulating sleeve 17, with corresponding openings 18, is mounted and adapted to turn thereon. By this means any area of opening necessary may be provided and the supply of air through said openings regulated to secure the proper mixture for obtaining the character of flame desired. The outer end of pipe 13 is provided with a nipple section 19 for attachment to the gas supply hose 20.

The door E shown in fig. 6 is of appropriate construction for use with solid fuel and is provided with air inlets 21 controlled by a sliding valve 22 operated by a handle 23 in a common manner.

The grate a is of special construction and adapted to perform a two-fold purpose. The form and construction will be best understood by an inspection of Figs. 2 and 4. It extends a greater part of the length of the combustion chamber and is wide at its rear end and narrow at its forward end, with longitudinal air spaces extending through its central portion and also through its shorter side portions. This character of grate has been found very efficient when the iron is used for solid fuel, such as charcoal, with the character of door shown in Fig. 6 and the air and draft regulating devices. It is also especially adapted for use with the particular character of gas burner D¹, the angularly positioned openings 14 directing the flame outwardly toward each side of the iron and the grate serving to spread the flame and deflect it over the entire bottom surface of the iron, thereby coöperating very efficiently with the particular character of burner, and to the efficiency of the iron when used with gas for the heating agent.

In operation, when it is desired to use said iron with gas as a fuel, the gas supply pipe 20 is attached to the gas supply. The valve controlling said supply (not shown) is opened and the gas mixed with an appropriate supply of air coming through the openings 16, controlled by the sleeve 17, comes through the angularly positioned openings 14 and is ignited at the outer end of burner D¹. The burner is lighted and the mixture regulated to secure the desired flame before the burner is inserted in the iron. The operator is thus conveniently enabled to adjust his flame and see that it is burning properly before the burner is placed in the combustion chamber. When this is done the door D is slid into place behind the overhanging flanges surrounding the entrance to the combustion chamber and may be locked in place by a button 30 mounted and adapted to turn on a screw 31 on the outer face of the rear handle post, or support. The downward inclination of the

burner D¹ directs the flame against the top surface of the bottom of the iron, while its flared outer end with the division 15 between the two sides thereof, coöperating with the particular form of grate a, which as now used serves as a flame spreader, insures that the flame will be spread substantially across the entire surface of said bottom, thus securing a uniform degree of heat throughout said surface, and a maximum amount of heat with a minimum quantity of gas. By this means very efficient work may be accomplished by the use of the iron without heating the iron excessively, enabling the upper part of the iron to be maintained at a comparatively low temperature and thus avoid, to a considerable extent, much of the discomfort commonly experienced in the use of the internally heated sad irons.

When it is desired to use charcoal, or similar fuel, door D is removed and the door E is then substituted therefor. The charcoal is introduced and lighted in the well known manner, and the draft regulating devices adjusted so that the combustion chamber will be adapted for burning such fuel, and the work will proceed in the well known manner.

Having thus fully described my said invention, what I claim as new and desire to secure by Letters Patent is:

1. A sad-iron comprising a body formed with an internal combustion chamber having an open side with vertical retaining grooves at each side of said opening, a sliding plate with edges adapted to be mounted in and slide in said grooves to engage therewith and disengage therefrom, and formed with a gas burner as an integral part thereof, said gas burner extending part on one side of said plate and part on the other and in a direction inclined inwardly toward the bottom of said combustion chamber, the inner end of said burner being formed flared and with a multiple of discharge openings leading at angles each way from the central opening and the outer end of said burner being formed for the attachment of a gas pipe, substantially as set forth.

2. A sad iron comprising a body formed with a combustion chamber with an opening at one end having an overhanging flange around its vertical sides and bottom, a sliding plate for closing said opening, of dimensions to normally pass through said opening, but formed with laterally projecting wings adapted to engage behind the vertical overhanging flanges when in closed position, and to be released from engagement with said flanges by a slight upward movement, said plate being also formed with a gas burner integral therewith and extending on each side thereof, the outer portion being formed for attachment with the gas supply pipe,

and the portion extending within the combustion chamber being formed to direct the flame over the surface of the combustion chamber adjacent to the operative surface of the iron, substantially as set forth.

3. A sad iron comprising a body formed with a combustion chamber with an opening at one end having flanges overhanging its vertical sides, which flanges are inclined 10 from the top inwardly toward the bottom, a sliding plate for closing said opening formed to fit behind and be retained by said flanges when in closed position, and to be released from said flanges when slid upwardly a short distance, whereby only a slight vertical movement is necessary to engage and disengage it from said retaining flanges, said plate being formed with a gas burner integral therewith and extending on 15 each side thereof, the outer portion being formed for attachment with the gas supply pipe, and the inner portion formed to project the flame appropriately within the combustion chamber, substantially as set forth.
4. In a sad iron adapted to be heated by either solid fuel, or gas, the combination of a combined grate and flame spreader formed wide at its rear end and narrow at its forward end and extending the greater part of 20 the length of the combustion chamber on the bottom thereof, and a gas burner having

attachments for connecting with the gas supply and formed as a part of a removable door to the combustion chamber, the burner being formed with angularly disposed openings to discharge a fan-shaped flame and positioned to discharge upon the top of the rear end of said combined grate and flame spreader, whereby said flame is spread over the bottom of the iron, substantially as set 25 forth.

5. An internally heated sad iron adapted for use with solid fuel or gas, comprising a combustion chamber, a combined flame spreader and grate mounted on the bottom 30 of said combustion chamber, a door to said combustion chamber, a gas burner mounted in said door and provided with means for connecting with the gas supply, said gas burner being formed with angularly disposed openings and arranged to discharge its flame upon the surface of said combined 35 grate and flame spreader, substantially as set forth.

In witness whereof, I have hereunto set 40 my hand and seal at Washington, District of Columbia, this second day of January, A. D. nineteen hundred and fourteen.
